UNITED STATES PATENT OFFICE.

JOHN BOOTH SUMNER, OF FORT WILLIAM, ONTARIO, CANADA.

BOTTLE-CAP REMOVER.

Application filed October 23, 1924, Serial No. 745,436. Renewed February 5, 1927.

The invention relates to improvements in bottle cap removers and particularly to a device for removing the customary cardboard cap utilized on bottles such as milk and

5 cream bottles, and an object of the invention is to provide a simply constructed, inexpensive and durable device which can be readily manipulated by the operator and which will effectively remove the cap and 10 without disturbing the contents of the bottle.

A further object is to construct the device so that no skill or care is required in operating it to remove the cap.

With the above more important objects 15 in view the invention consists essentially in the arrangement and construction of parts hereinafter more particularly described, reference being had to the accompanying drawing in which:

20 Fig. 1 is a vertical sectional view centrally through the appliance as it appears applied on the bottle cap and in the initial position, the spear point being shown in side elevation.

25 Fig. 2 is a view similar to Figure 1 showing the position taken by the parts after the spear point has been depressed to pass through the cap.

Fig. 3 is a view similar to Figure 2, but 30 showing the device in the position which it occupies when one is ready to withdraw the caught cap.

Fig. 4 is a horizontal sectional view at 4-4' Figure 1.

35 Fig. 5 is a perspective view of the bottle cap remover.

In the drawing like characters of reference indicate corresponding parts in the several figures.

40 It is well known that cardboard caps are utilized for sealing bottles such as milk bottles and that difficulty is experienced in removing the caps as they are tightly seated in the neck of the bottle and lie directly over

45 the liquid contained therein. The present device is provided to permit one to easily remove the cap and without disturbing the contents of the bottle and it is constructed as hereinafter described.

50 A rigid bearing or base plate 1 is provided, this being disc-shaped and having a diameter somewhat less than the open end 2 of the bottle neck 3. As is customary, the

55 bottle neck is provided with an internal seat 4 on which the bottle cap 5 rests and the plate 1 is adapted to take a position directly

on top of the cap and with the edges thereof just nicely clear of the neck of the bottle to allow of the ready removal or insertion of the plate.

The plate is provided with a central bridge 6 and the bridge is provided with a centrally positioned opening 7 which receives slidably a plunger or shank 8, the lower end of which is fitted with a spear point 9 which is, in the present instance, cone-shaped. The spear point is normally positioned between the upper part of the bridge and the cap, and the cap is provided with a centrally positioned opening 10 which is large enough to permit of the passage through the plate, of the spear point. The upward travel of the spear point is limited by the spear point striking the bridge. The upper end of the shank terminates in a finger ring 11 and between the ring and the plate I locate a coil spring 12, the lower end of which encircles the bridge. This spring normally holds the spear point in its uppermost position or as best shown in Figure 1.

When it is desired to remove the bottle cap 5, one places the plate 1 on top of the cap and it will be here observed that the outer edge of the plate overlies the seat 4 above the cap so that any down pressure on the plate is transmitted directly through the cap to the seat. The plate having been put in place, one then forces the shank downwardly to pass the spear point through the cap, the position of the parts then appearing as shown in Figure 2. This being accomplished, one releases the plunger and the spring draws the spear point upwardly, the cap being then caught between the enlarged end of the cone-shaped point and the plate. One then lifts the device and the cap is withdrawn therewith. The withdrawn cap can be readily removed from the spear point subsequently.

From the above description, it will be readily seen that one can very easily and quickly remove the cap and that there is no possibility of the liquid contents of the bottle being squirted on the operator as the plate 1 holds the edge of the cap tightly down against the seat when the plunger is being depressed.

What I claim as my invention is:

A bottle cap remover comprising a base plate provided with a central opening, a bridge member including oppositely directed

2
foot portions arranged at opposite sides of said openings, vertical portions extending upwardly from the inner ends of said foot portions, a horizontal portion connecting the upper extremities of the vertical portions and formed with a central opening smaller than the opening in the base plate and disposed in registration therewith, a vertically disposed shank passing slidably through the opening in the bridge member and terminating at its lower end in a spear point larger than said last named opening but smaller than the opening in the base plate whereby upward movement of the spear point is limited by contact with the horizontal portion of the bridge member, said spear point being of such length as to pro-

ject but slightly below the base plate when disposed in raised position between the vertical portions of the bridge member, a handle formed at the upper end of said shank and a spring confined between the handle and the foot portions of the bridge member and encircling the vertical portions of the bridge member so as to be thereby held in concentric relation with the shank, said spring serving to normally hold the shank in elevated position with the spear point engaging the horizontal portion of the bridge member. 30

Signed at Fort William, Ontario, this 12th day of April, 1924.

JOHN BOOTH SUMNER.
